APPARATUS FOR TREATING KRAUT

Application filed February 16, 1925. Serial No. 9,466.

This invention relates in general to improvements in the art of treating food, and relates more specifically to improved apparatus for conditioning, preserving and packing fibrous or stringy substances such as sauer kraut, although some of the novel features are capable of more general application.

Generally stated, an object of the invention is to provide simple and efficient apparatus for preparing, feeding, measuring and packing edible substances, especially sauer kraut.

- Some of the more specific objects of and advantages attainable with the present improvement, are as follows:
- 15 To provide apparatus for conditioning and packing sauer kraut in receptacles, whereby all of the useful ingredients of the commodity, including the original juice, may be utilized and retained in the final product.
  - 20 To provide an efficient machine for preserving sauer kraut and for packing the treated material in order to eliminate subsequent spoilage.

- To provide improved kraut measuring mechanism which will rapidly and accurately produce successive equal and homogeneous batches of such material, and which will automatically deliver the measured batches in succession, to receptacles such as cans.
- 25 To provide new and useful automatic feeding mechanism for delivering fibrous material such as kraut, into the successive pockets of the measuring mechanism.

- To provide improved mechanism for feeding receptacles such as cans, in succession through a can filling machine.

- To provide simple, efficient and flexible driving mechanism for the feeding and measuring mechanisms of the improved kraut treating machine.

- To provide improved instrumentalities whereby the operating characteristics of a can filling machine may be readily varied to accommodate receptacles of various sizes.

- 45 To provide a filling machine various parts of which are conveniently removable for inspection, and all parts of which are readily accessible for cleaning.

- To provide various other improvements in the details of construction and operation of

can filling machines whereby the cost of construction is reduced to a minimum and the efficiency of operation is enhanced to a maximum.

These and other objects and advantages will be apparent from the accompanying description.

Some of the novel features of kraut treating processes and machines, disclosed but not claimed herein, form the subject of copending applications Serial No. 634,196, filed April 23, 1923, and Serial No. 741,212, filed October 2, 1924.

A clear conception of the various steps of the improved process and of the details of construction and operation of a device embodying the present improvements, may be had by referring to the drawings accompanying and forming a part of this specification in which like reference characters designate the same or similar parts in the various views.

Fig. 1 is a central vertical section through the kraut feeding, measuring, can feeding and driving mechanisms of the improved kraut treating machine.

Fig. 2 is a top view of the improved kraut treating machine.

Fig. 3 is a fragmentary plan view of the improved kraut treating machine showing the details of construction of the can feeding and driving mechanisms.

Fig. 4 is a fragmentary vertical section taken along the central vertical plane of the can supply chute of the improved kraut treating machine.

Fig. 5 is a fragmentary horizontal section through the kraut feeding and measuring mechanisms of the improved treating machine.

Fig. 6 is an enlarged fragmentary vertical section taken transversely across the kraut feeding and driving mechanisms of the improved treating machine.

Fig. 7 is an enlarged elevation of a set of the conveying or raking fingers of the improved kraut feeding mechanism.

Fig. 8 is a development of the improved measuring mechanism showing the positions assumed by the successive plungers of the improved kraut treating machine.

Fig. 9 is an enlarged vertical section through fragments of the improved kraut feeding and measuring mechanisms of the machine.

5 Fig. 10 is an enlarged horizontal section through fragments of the improved kraut feeding and measuring mechanisms of the machine.

10 Fig. 11 is an enlarged vertical section taken transversely through the upper forward portion of the kraut supply hopper of the improved treating machine, showing a fragment of the finger operating mechanism associated therewith.

15 Fig. 12 is a fragmentary vertical section through one of the measuring pockets during elevation of the plunger therein.

20 Fig. 13 is a fragmentary vertical section through one of the measuring pockets during delivery of liquid thereto.

25 Fig. 14 is a fragmentary vertical section through one of the measuring pockets during topping of the mixture of kraut and liquid within a can.

30 Fig. 15 is a fragmentary vertical section through one of the measuring pockets during recession of the plunger therein immediately after topping.

Fig. 16 is an enlarged horizontal section 35 through cooperating fragments of a measuring pocket, plunger and confining wall.

Fig. 17 is an enlarged fragmentary view of one of the kraut raking fingers showing the driving end thereof.

35 Fig. 18 is an enlarged fragmentary sectional view showing details of construction of a set of the kraut raking fingers and of the driving mechanism associated therewith.

40 Fig. 19 is a fragmentary side elevation of the improved kraut treating machine showing details of construction of the power and liquid control mechanisms.

45 Fig. 20 is a diagrammatic view showing one form of apparatus for effecting practical exploitation of the improved process of conditioning, measuring and packing kraut.

Fig. 21 is a diagrammatic transverse vertical sectional view through an improved automatic bleaching and sterilizing machine.

50 Referring specifically to Figs. 1 and 2 of the drawing, it will be apparent that the improved kraut treating machine comprises generally measuring mechanism for automatically producing successive equal and homogeneous batches of mixture of conditioned kraut and liquid and for successively discharging the batches; automatic kraut feeding mechanism for continuously urging masses of the kraut fibres in ribbon formation toward the measuring mechanism; automatically functioning mechanism for delivering a mixture of original juice and brine to the measuring mechanism; mechanism for automatically conveying cans 38 in succession to, through 55 and from the machine; and driving mecha-

nism for imparting motion to the various material and can treating mechanisms.

The automatic measuring mechanism consists of a stationary annular wall or casing 10 having an integral bottom provided with an elongated discharge opening 75; a rotary measuring element 40 mounted centrally within the casing 10 and having formed

70 therein an annular series of six equally spaced measuring pockets 7 each having an open side normally closed by the casing 10; a vertically reciprocable displacement plunger 8 located within each of the measuring pockets 7; mechanism for intermittently advancing the pockets 7 step by step, about the central vertical axis of the casing 10; and a series of cams associated with the casing 10 for moving the plungers 8 during movement of the pockets 7.

75 The stationary casing 10 is detachably supported by the main frame 28 of the machine and has an opening through one side thereof communicating with the enlarged delivery end of a gradually enlarging or tapered kraut supply conduit 5, see Fig. 10.

80 The annular vertical wall which forms the casing 10 is of variable height and cooperates with the vertically adjustable but normally stationary tracks or cams 87, 88, 64, 90, 91, 93

85 which are engageable with rollers 83 to reciprocate the plungers 8 during advancement thereof about the casing axis, see Fig. 8. The cams 87, 88, 93 are formed integral with each other and are simultaneously vertically adjustable by means of screw jacks 89. The

90 cams 64, 90 are likewise formed integral with each other and are simultaneously vertically adjustable, independently of the cams 87, 88, 93, by means of screw jacks 89. The cam 91

95 is formed integral with the casing 10 and the track 92 is formed directly upon the casing wall. The rollers 83 are carried by pins on the upper ends of the plungers 8, and the plungers are formed of several parts as

100 shown in Fig. 16. The main body of each plunger 8 is slidably fitted within the corresponding pocket 7 and has a wearing shoe 70 secured thereto by means of a pin 72. Each

105 wearing shoe 70 has parallel sides cooperating with guide surfaces of the element 40, and has a curved outer surface engageable directly with the bore of the casing 10. The plungers 8 are thus effectively guided and held against rotation. The plungers 8 are freely

110 vertically removable from the pockets 7 when the rollers 83 are out of engagement with the cams 87, 90, and the pocket element 40 is likewise freely vertically removable with the aid of handles 80. The center of the element 40 is bored to receive the upper extremity of the vertical driving shaft 11 which has

115 a rectangular drive head 69 disposed within a lower recess in the element 40. The driving shaft 11 is mounted in bearings in the main frame 28 and has a horizontal driving disk 120

125 13 rigidly attached to a medial portion there-

of. The disk 13 carries a series of six rollers 44 which are successively cooperable with a cam slot formed in a rotary driving member 14. The member 14 is mounted upon a transverse horizontal drive shaft 15 supported in bearings in the main frame 28, and the cam slot formed in the member 14 is so shaped that continuous rotation of the shaft 15 and member 14 causes intermittent stopping and movement of the shaft 11 and element 40 through angles of 60 degrees about the axis of the casing 10.

The automatic kraut feeding mechanism consists of a casing forming a horizontally tapered chamber 4 and a horizontally oppositely tapered discharge conduit 5 communicating with the chamber 4 at a point of constriction; a supply hopper 2 having a downwardly diverging discharge portion 3 communicating 20 with the top of the chamber 4; and a plurality of simultaneously oscillatable and reciprocable feeding or raking fingers 6, 76 for urging dry kraut in ribbon formation through the chamber 4 and the conduit 5, see Figs. 1, 2 and 5. The casing which forms the chamber 4 and the conduit 5 is mounted upon the main frame 28 and is attached to the stationary measuring casing 10. The fingers 6 are slidably associated with transverse openings 25 in pivots 66 which are oscillatably retained in vertical bores at the opposite sides of chamber 4. The pivots 66 are held in the bores by gravity alone and are freely vertically removable as shown in Fig. 6. The 30 free ends of the side fingers 6 are movable in horizontal looped paths within the chamber 4 as shown in Fig. 5, and the opposite ends of these fingers are provided with reduced portions 73 which are loosely attached to vertical pins 68 as shown in Fig. 17. The 35 pins 68 are carried in frames 65 and rest upon horizontal angle bars as shown in Fig. 18. The frames 65 are detachably connected to vertical bearing sleeves by means of clamping 40 bolts 67 as shown in Fig. 6, and the sleeves embrace vertical crank pins 74 the opposite ends of which are mounted in eccentric bearings in the rotary driving disks 9, 71. The 45 upper disks 71 are rotatably supported in removable stationary top frames 82 and the lower disks 9 are attached to the upper ends of vertical drive shafts 46, 47. The free ends of the top fingers 76 are movable in vertical looped paths within the chamber 4 as shown 50 in Fig. 9, and the opposite ends of these fingers are loosely attached to a crank pin 84. The crank pin 84 is carried by laterally spaced cranks 78 which are attached to horizontal crank shafts 79. One of the crank shafts 79 55 is drivingly connected to one of the upright shafts 86 by means of bevel gearing 85 as shown in Fig. 2. The top fingers 76 penetrate a horizontal pivot 77 which is oscillatably mounted in the casing forming the chamber 4.

60 The automatically functioning mechanism

for delivering the liquid to the successive measuring pockets 7 consists of a liquid reserve tank 31 having an upper inlet 32 and a lower discharge 39; a manifold 62 communicating directly with the tank discharge 70 39; and a grid 63 formed integral with the casing 10 and communicating directly with the manifold 62. The flow of liquid to the tank 31 is controllable by means of a valve 41 operable by a lever 81 secured to one end of a pivot rod 161 the opposite end of which forms a support for the main power control lever 19 of the machine, see Figs. 2 and 19. With this arrangement of elements, the supply of liquid to the tank 31 is automatically 75 cut off when the machine is stopped and vice versa. The mixture of original kraut juice and brine may be derived from a combined bleaching and sterilizing machine such as shown in Figs. 20 and 21 and comprising an 80 enclosed casing 33 having a supply hopper 34 for supplying juice laden kraut and a brine inlet pipe 36 for supplying regulable quantities of heated brine thereto. The casing 33 has an inclined bottom and a conveyor 85 or rake 35 cooperates with this bottom to remove the dry kraut fibres from the liquid within the casing 33 and to deliver the fibrous material into the hopper 2 of the filling machine. The liquid supply or inlet 32 90 of the tank 31 communicates with the liquid basin within the chamber 33 and may be provided with a flow control valve and a heater 37 for heating the mixture of original juice and brine delivered to the tank 31.

The mechanism for automatically conveying the cans 38 in succession to, through and from the filling machine consists of a can supply chute 42 formed to automatically right the successive cans 38; a continuously 100 rotatable frusto-conical can feed drum 29 mounted upon the horizontal transverse shaft 15 and having a helical can conveying projection 26 formed integral with the delivery end thereof; an annular series of six equally spaced and intermittently movable can hooks 12 detachably secured to the vertical main shaft 11 below the casing 10; a continuously 105 rotatable horizontal can discharge disk 30 secured to the upper extremity of a vertical drive shaft 58; and normally stationary but readily adjustable can guides 61, 43, 57 associated with the feed drum 29, with the can hooks 12, and with the discharge disk 30, respectively, see Figs. 1, 2 and 3. The can supply chute 42 communicates with a suitable source of supply and cooperates with the feed drum 29 to continuously deliver empty cans 38 in succession and at a predetermined rate of speed toward the path of the can hooks 12. The can hooks 12 are intermittently movable with the shaft 11 and the pockets 7, and are formed to receive the cans 38 in succession from the feed drum 29 with their central axes in vertical alinement with 110 120 125 130

the axes of the successive plungers 8. The can discharge disk 30 cooperates with the can hooks 12 to continuously remove the successive filled cans 38 from the path of movement of the hooks, and is adapted to deliver the cans from the machine. The can guides 61, 57 are angularly adjustable about vertical pivots, and all of the guides 61, 43, 57 are readily removable.

10 The driving mechanism for imparting motion to the various elements of the filling machine, consists of a continuously rotatable main horizontal drive shaft 16 supported in bearings in the frame 28; a drive pulley 17 and an idler pulley 18 associated with one end of the drive shaft 16 in a well known manner; a belt shifter 59 operable by the control lever 19 to shift a belt which cooperates with the pulleys 17, 18; a worm 52 secured to a 15 medial portion of the shaft 16 and meshing with a worm wheel 53 secured to the transverse horizontal shaft 15 to impart continuous rotary motion to the said shaft; a spur gear 27 and a hand wheel 60 associated with 20 the opposite end of the drive shaft 16; a counter shaft 25 extending parallel to the drive shaft 16 and having a spur gear 24 which meshes with the gear 27, secured to one end thereof; a cross-shaft 21 extending 25 parallel to the shaft 15 and having a medial bevel gear 22 which meshes with a bevel gear 23 secured to the opposite end of the shaft 25; and a pair of horizontal auxiliary shafts 45 drivingly associated with end portions of 30 the cross shaft 21 by means of bevel gears 48, 50, see Fig. 3. The grooved pocket and can hook driving member 14 and the can feed drum 29 are secured to and continuously rotatable with the transverse shaft 15, while 35 bevel gears 54 associated with an end of the shaft 15 are capable of imparting continuous rotation to the discharge disk driving shaft 58 through a counter shaft 55, a worm 20, and a worm wheel 56. The spur gears 27, 24 40 are readily removable from the shafts 16, 25 and may be replaced by gears having a different number of teeth in order to change the relative speed of the shaft 25 and the mechanism driven thereby. The hand wheel 60 provides means for manually operating 45 the mechanism when the power is thrown off. The continuous rotary motion of the cross shaft 21 is transmitted through the bevel gears 48 which are secured thereto, to the bevel gears 50, and the vertical shafts 46 associated therewith, and from these latter gears to the shafts 45 through the bevel gears 48 secured thereto. The rotary motion of the shafts 45 is transmitted through bevel gears 55 49, 51 to the vertical shafts 47.

During normal operation of the mechanism to carry on practical exploitation of the improved process, the juice laden kraut is delivered from the vats through the hopper 34 to the automatic bleacher and sterilizer 33.

In the sterilizer 33, a desired amount of brine is added and the mixture of kraut, juice and brine is agitated and heated sufficiently to thoroughly bleach and sterilize the entire mixture. The kraut fibres after being treated, are continuously removed from the mixture by the raking mechanism 35 and are delivered in hot condition through the hopper 2 to the feeding chamber 4. Simultaneously with the removal and discharge of the heated kraut fibres, a definite quantity of the residual mixture of brine and original juice is being delivered by gravity from the sterilizer 33 through the filler supply pipe 32 to the reserve tank 31, and from the tank 31 70 through the discharge pipe 39 to the manifold 62. While passing through the pipe 32, the liquid may be additionally heated by means of the heater 37.

As the main drive shaft 16 is continuously 75 rotated by means of power applied at the drive pulley 17, the improved driving mechanism automatically functions to simultaneously cause the inner free ends of the fingers 6, 76 to travel paths such as illustrated in 80 Figs. 5 and 9 to continuously rotate the can feed drum 29 and the discharge disk 30; to intermittently advance the measuring pockets 7 and the can hooks 12 step by step about the axis of the shaft 11; and to reciprocate the plungers 8 within the pockets 7. The hot kraut fibres admitted to the chamber 4 are raked into substantially parallel ribbon formation by the simultaneously oscillating and reciprocating fingers 6, 76, and are gradually advanced through the chamber 4 by the successive fingers 6 located at opposite sides of the feeding chamber. These fingers function without tearing the kraut fibres and as one superposed set of fingers 6 is withdrawn 85 from a mass of fibres, it leaves openings which are subsequently entered by a succeeding set of fingers of the same series. As the ribbon of kraut fibres proceeds toward the smaller end of the chamber 4, it is eventually forced past the constricted discharge opening thereof into the conduit 5. Due to the progressively gradual enlargement of the conduit 5, the ribbon of substantially parallel 90 kraut fibres passing therethrough, automatically expands slightly, in a manner similar to the expansion of material passing between the rollers of a wringer, and is delivered at the side inlet opening of the casing 10 in the form of a gradually advancing stream of dry 95 fibres of uniform texture.

The measuring pockets 7 are presented in 100 succession with their open sides in open communication with the discharge end of the conduit 5 and are momentarily stopped with 105 the plungers 8 therein in upper position as shown in Fig. 1 and at the extreme ends in 110 Fig. 8. The advancing kraut fibres enter the 115 presented pocket 7 while at rest, substantially filling the space below the plunger 8. When 120

5 a pocket 7 has been thus filled with a batch of fibres of definite volume, the pocket is advanced and the trailing edge thereof automatically cooperates with the edge of the casting 10 to cut the measured batch of fibres from the advancing ribbon, as clearly shown at 96 in Fig. 10. The forward movement of the filled pocket 7 causes the plunger 8 therein to move downwardly and to slightly compress the confined batch of fibres by virtue of engagement of the plunger roller 83 with the cam track 87, see Fig. 8. As the moving kraut filled pocket 7 is exposed to the liquid supply grid 63, the roller 83 of the plunger 8 rides up the upwardly inclined forward end of the cam track 64 and again elevates the plunger, thereby permitting the mass of kraut fibres to expand slightly and causing a quantity of the hot liquid to enter the pocket 7 10 from the manifold 62. When the kraut laden pocket 7 has been brought in full communication with the liquid supply grid 63, it is again momentarily stopped thus insuring complete filling of the pocket with a definite quantity 15 of mixed kraut and liquid. After being thus completely filled, the measuring pocket 7 is again advanced with the plunger 8 held in fixed upper position by the cam track 64, until the bottom of the pocket 7 is exposed to a can 38 through the discharge opening 75. As 20 soon as the pocket 7 has been thus fully exposed, the pocket is again momentarily stopped to permit the liquid to flow by gravity into the can 38 below. Upon further advancement of the pocket 7, the roller 83 of 25 the corresponding plunger 8 engages the successive cam tracks 90, 91 and is moved downwardly, thereby positively forcing the remainder of the measured batch of kraut and brine from the pocket 7 into the can 38. The 30 plunger 8 and the pocket 7 are then again momentarily stopped after which further movement of the pocket 7 causes the plunger 8 to move downwardly by virtue of engagement with the lower portion of the cam track 91, through the opening 75 and into the can 38 thus topping the material within the filled can. After topping, the movement of the plunger 8 is reversed, the plunger being withdrawn from the can through the opening 75 35 until the roller 83 engages the horizontal track 92 whereupon the pocket 7 and the plunger 8 are again momentarily stopped. During the succeeding motion of the pocket 7, the plunger 8 is advanced to the upwardly inclined forward portion of the elevating cam track 93, whereupon a complete cycle 40 of operations has been completed and successive repetitions thereof occur. It will be apparent that each of the series of pockets 7 and plungers 8 pass successively through the same cycle thus automatically filling the successive cans 38 with homogeneous batches of mixture of kraut fibre and mixed brine and 45 original juice.

The successive empty cans 38 are gradually presented to the successive intermittently advancing can hooks 12 by the continuously rotating feed drum 29 and the can guide 61, without danger of damaging the same. The can hooks 12 being driven by the intermittently revolving shaft 11, advance the cans 38 step by step simultaneously with the pockets 7. The guide 43 coacts with the cans 38 during filling thereof as shown in Fig. 3. After the cans 38 have been properly filled, they are delivered in succession by a fixed cam as shown in Fig. 3, to the continuously rotating can discharge disk 30 from which they are discharged by the can guide 57. It 50 will be apparent that while the can feed drum 29 and the discharge disk 30 operate continuously, to supply and discharge the cans, the can hooks 12 cooperating therewith, operate intermittently in order to insure alignment thereof at all times with the measuring pockets 7 and the plungers 8.

From the foregoing description it will be apparent that the entire mechanism performs its function automatically and effectively. The combined bleacher and sterilizer 33 properly conditions the material and separates the kraut fibres from the juice, thus permitting independent and accurate measurement of the solids and liquids and 55 insuring accurate proportioning of the constituents in each final batch of mixture. The constriction in the hopper 2 besides producing uniform consistency of the mass of kraut fibres delivered into the feeding chamber 4, also regulates the feed when the machine is being supplied with a proper amount of kraut. By enlarging the portion 3 of the supply hopper 2, the kraut fibres are permitted to drop by gravity and with minimum resistance, toward the feed chamber 4, and the hopper 2 is quickly removable to expose the chamber 4. The kraut feeding fingers 6 located at opposite sides of the chamber 4, travel toward each other when feeding, thus urging the kraut fibres away from the side walls and toward the center of the chamber 4, and automatically arranging the fibres in ribbon formation. Since the fingers 6 on opposite sides of the chamber 4 are movable in unison and are travelling in like direction, the fibres are continuously and gradually advanced toward the conduit 5. It will also be apparent that the fingers 6 are substantially equi-distant apart 60 and have practically equal throw, thus causing successive sets of fingers 6 to take hold where the preceding sets left the mass of fibres, thus avoiding any tendency to tear the frail fibres. By causing the fingers 6 to travel away from the center of the chamber 4 on the return stroke, obstruction to entry of the kraut mass is also avoided and the fibres freely assume a proper position 65 preparatory to feeding. The drive for the 70

105

110

115

120

125

130

fingers 6 is extremely effective and the rate of feeding may be readily varied by changing the gears 27, 24 at the ends of the shafts 16, 25 respectively.

5 By causing the pistons 8 in the measuring pockets 7 to compress and to return excess kraut fibres to the conduit 5 until just prior to the point of cut-off as shown at 96, a minimum number of fibres are actually cut as each batch is severed from the mass. When the plungers 8 are elevated to admit liquid after compression, a definite quantity of liquid is admitted, depending upon the position of vertical adjustment of the cam track 64. If a relatively dry pack is desired, the track 64 may be placed in its lowermost position, whereas elevation of the track 64 increases the proportion of liquid admitted. By admitting the liquid through a grid 63 to all vertical sections of the measured batches of kraut fibre, complete filling of each measuring pocket 7 is assured. Variation in volume of the measured batches as well as variation in the proportions of the constituents, may be readily secured by varying the position of the cam tracks 87, 88, 64, 90, 93 with the aid of the jack screws 89. The use of stationary cam tracks obviously reduces the construction to its simplest form and permits ready removal of the plungers 8 and of the element 40. The cam track is also simplified by utilizing the upper end of the casing 10 as a track and by making only certain sections independently adjustable. By 30 forming the plungers 8 relatively flat sided, feeding of the cans 38 from the side, is facilitated. The guide plates 70 act as keys to prevent the plungers 8 from rotating due to lateral pressures on the rollers 83, and the rollers may obviously be placed relatively near to the plunger axes, thus causing them to elevate the plungers without buckling. The flat sided plungers 8 and pockets 7 also permit free escape of air from the cans 38 when the flat sided batches of fibre are dropped into the cans thus enhancing the permissible speed of operation.

It will thus be noted that the various elements of the structure are formed to effectively perform their several functions. When the machine is operating normally, a constantly uniform stream of heated brine and juice is being withdrawn from the sterilizer 33 and a substantially constant supply of brine may be admitted to the sterilizer. The machine may be quickly stopped by moving the lever 19 which also controls the liquid supply valve 41. If it is desired to inspect or clean any part of the mechanism, covering structure may be readily removed. The hopper 2, plungers 8, element 40, fingers 6, 76, pivots 66 and the several adjustable cam tracks are obviously readily removable to expose the entire interior of the feeding and measuring mechanism. The can guides 61,

43, 57 and the guide for conducting the cans 38 from the hooks 12 onto the disks 30, as well as the can hooks 12 and the discharge disk 30 are also freely removable. The driving mechanism is readily accessible at all times without removing other parts, thus making all elements conveniently accessible.

While the invention has been described as being specifically applied to a kraut filling machine, it will be apparent that various of the novel features are capable of general application to other classes of filling and conditioning machines. It should be understood that it is not desired to limit the invention to the exact steps of the process or to the precise detail of construction of apparatus herein shown and described, for various modifications within the scope of the claims may occur to persons skilled in the art.

It is claimed and desired to secure by Letters Patent:—

1. In combination, a series of measuring pockets movable about an axis, a plurality of movable fingers formed to fill the successive pockets of said series while at rest with loose masses of dry kraut, means for subsequently adding sufficient liquid to the kraut confined within successive pockets of said series to fill the spaces between the kraut fibres and means for delivering the successive measured quantities of kraut and liquid to receptacles.

2. In combination, a series of measuring pockets movable about an axis and each having a side inlet opening, a plurality of movable fingers formed to fill each of said pockets while at rest through said openings with dry kraut, means for subsequently delivering sufficient liquid into each of said pockets through said opening to produce measured batches of mixture, and means for delivering said batches to successive receptacles of a series through the ends of said pockets.

3. In combination, a series of measuring pockets, means for intermittently moving said pockets, means for filling each of said pockets while at rest with loose masses of dry kraut, and means for subsequently delivering sufficient liquid into each of said pockets while at rest to fill the spaces between the kraut fibres.

4. In combination, a measuring pocket, means for intermittently moving said pocket, a plunger within said pocket, plural means for independently delivering fibrous and liquid material to said pocket while at rest, and means for moving said plunger while said pocket is in motion.

5. In combination, a measuring pocket, means for intermittently moving said pocket to different positions relatively to an axis, plural means for independently delivering fibrous and liquid material to said pocket while at rest, and a plunger movable within said pocket to act upon said material only while said pocket is in motion.

6. In combination, a series of measuring pockets intermittently and successively movable from one position to another, means for delivering solid material to successive pockets of said series while at rest, means for delivering liquid to successive pockets of said series while at rest, and a plunger movable within each of said pockets only while in motion.
7. In combination, an annular series of intermittently movable measuring pockets, means for delivering solid material to the successive pockets while at rest, means for subsequently delivering liquid to the successive pockets while at rest, and a plunger movable longitudinally within each of said pockets while in motion.
8. In combination, an annular series of measuring pockets revoluble about an axis, said pockets having their sides located remote from said axis open, means for delivering solid material to the successive pockets through said open sides, means for subsequently delivering liquid to the successive pockets through said open sides, and a plunger intermittently movable within each of said pockets.
9. In combination, an annular series of measuring pockets each having an opening at the side, means for intermittently moving said pockets in succession, plural means for independently delivering fibrous and liquid materials to said pockets through said openings while said pockets are at rest, and a plunger movable within each of said pockets only while in motion.
10. In combination, an annular series of measuring pockets each having an opening at the side, means for intermittently moving said pockets in succession about an axis, means for delivering fibrous material to the successive pockets through said openings while said pockets are at rest, means for subsequently delivering liquid to the successive pockets through said openings while said pockets are at rest, and a plunger movable within each of said pockets during movement thereof.
11. In combination, means forming a horizontally tapered chamber, a vertically tapered hopper having the larger end of said tapered portion located directly adjacent to the top of said chamber, and means for urging material delivered to said chamber from said hopper toward the smaller end of said chamber.
12. In combination, means forming a chamber of gradually decreasing cross-sectional area toward an end thereof, simultaneously oscillatable and reciprocable fingers located on opposite sides of said chamber, and a simultaneously oscillatable and reciprocable finger located above said chamber, said fingers being formed to urge material through said chamber in the direction of its constriction.
13. In combination, means forming a chamber having an end discharge opening, and a plurality of movable fingers extending into said chamber from three sides, said fingers being movable to urge fibrous material in ribbon formation through said chamber and said opening.
14. In combination, a casing having a plurality of bores therein, a pivot oscillatable in each of said bores, a finger slidably laterally through each of said pivots, and a frame for simultaneously moving corresponding outer ends of all of said fingers to cause the inner ends thereof to simultaneously feed material in the same direction.
15. In combination, a casing having a plurality of parallel bores therein, a pivot oscillatably supported in each of said bores, a finger slidably supported by and laterally penetrating each of said pivots, and a frame for simultaneously moving corresponding outer ends of said fingers through circular paths to cause the inner ends thereof to simultaneously feed material in the same direction.
16. In combination, a casing having a plurality of bores therein, a pivot supported in each of said bores, a finger laterally penetrating each of said pivots, driving means for moving said fingers, and a single frame coacting with all of said fingers and detachably associated with said driving means.
17. In combination, a casing, a plurality of fingers penetrating a wall of said casing, vertical pivot pins secured to corresponding ends of said fingers, and a common support engaging the lower ends of all of said pins.
18. In combination, a casing, a plurality of substantially parallel fingers penetrating each of the opposite side walls of said casing, vertical pivot pins secured to corresponding ends of said fingers, and a support common to all of said pins.
19. In combination, a casing, a plurality of parallel fingers penetrating a side wall of said casing and lying in a horizontal plane, a pair of laterally spaced simultaneously revoluble crank pins, and a driving connection between said pins and all of said fingers.
20. In combination, a casing, a plurality of parallel fingers penetrating the opposite side walls of said casing and lying in a horizontal plane, a pair of cooperating laterally spaced and simultaneously revoluble crank pins disposed on each side of said casing, and common means for simultaneously revolving all of said pins to move said fingers on opposite sides of said casing in the same direction relatively thereto.
21. In combination, an annular series of measuring pockets each having a side inlet opening, means for delivering relatively dry fibrous material into each of the successive

pockets through said opening, and means for subsequently delivering liquid into each of said pockets through said opening.

22. In combination, a measuring pocket revoluble about an axis and having a side inlet opening remote from said axis, means for delivering relatively dry fibrous material into said pocket through said opening, means for subsequently delivering liquid into said pocket through said opening, and means for subsequently delivering the mixture from said pocket.

23. In combination, a measuring pocket revoluble about an axis, said pocket having a side inlet opening and an end discharge opening, plural means for delivering relatively dry fibrous material and liquid into said pocket through said side opening at different times, and means for simultaneously discharging said materials from said pocket through said end opening.

24. In combination, a casing comprising a wall having solid and liquid material supply openings at spaced portions thereof, and a measuring pocket successively movable to a position of communication with and rest at said openings.

25. In combination, an annular casing having spaced solids and liquid inlet openings therein, and an annular series of measuring pockets intermittently movable to positions of communication with and rest at said openings.

26. In combination, a casing comprising an annular wall having cam tracks at an end thereof, a member forming series of pockets movable within and having one side bounded by said wall, and a plunger in each of said chambers intermittently movable in direct contact with said wall and said member by engagement with said tracks.

27. In combination, a casing comprising an annular wall, a series of cam tracks associated with an end of said wall, a member forming an annular series of measuring pockets intermittently movable within and having one side bounded by said wall, and a plunger movable within each of said pockets in direct contact with said wall and said member during movement thereof by virtue of engagement with said tracks.

28. In combination, a casing comprising an annular wall, a series of cam tracks associated with the upper end of said wall, a member forming an annular series of measuring pockets intermittently movable within and having one side bounded by said wall, a plunger within each of said pockets movable by said tracks in direct contact with said wall and said member, and means for effecting vertical adjustment of said tracks to vary the stroke of said plungers.

29. In combination, a measuring pocket having a parallel sided side opening, a flat sided plunger movable within said pocket,

and a removable guide associated with said plunger and coacting with the parallel sides of said opening to prevent rotation of said plunger within said pocket.

30. In combination, a cylindrical measuring pocket having a side opening provided with parallel sides, a flat sided plunger snugly fitting said pocket, and a removable plunger guide coacting with said pocket at said opening sides.

31. In combination, a measuring pocket having two side surfaces of different curvature, means for revolving said pocket about the center of greatest curvature, and a plunger comprising parts fitting said surfaces.

32. In combination, a measuring pocket having intersecting side surfaces of different curvature, means for revolving said pocket about the center of greatest curvature, and a two part plunger snugly fitting said surfaces.

In testimony whereof, the signature of the inventor is affixed hereto.
